UNITED STATES PATENT OFFICE.

DANIEL N. PRIME, OF LYNN, MASSACHUSETTS, ASSIGNOR TO UNITED SHOE MACHINERY COMPANY, OF PATERSON, NEW JERSEY, A CORPORATION OF NEW JERSEY.

METHOD OF MAKING ARTICLES OF METAL

1,114,384.

Specification of Letters Patent.

Patented Oct. 20, 1914.

Application filed November 24, 1908. Serial No. 464,226.

To all whom it may concern:

Be it known that I, DANIEL N. PRIME, a citizen of the United States, residing at Lynn, in the county of Essex and Commonwealth of Massachusetts, have invented certain Improvements in Methods of Making Articles of Metal, of which the following description, in connection with the accompanying drawings, is a specification, like reference characters on the drawings indicating like parts in the several figures.

This invention relates to a new method of forming articles of metal of that class in which the blank from which the article is to be made undergoes a change from one form or shape to another during the manufacture of the article, and is especially applicable to the manufacture of articles of such class from iron or steel, although no means limited to the use of that metal.

In making articles, such as above referred to, from steel, it is usual to bend the blank to the shape desired in the finished article before it is tempered or hardened, in cases where it is desired that the finished article be hardened, as after the hardening, the steel is more difficult to bend and has also become somewhat brittle and apt to break if bent more than a certain amount from its original form or shape. This bending of the soft or unhardened steel to the shape desired is usually performed while the portion of the blank at which the bending is to occur is heated to a red heat and thereafter the blank sets as it cools and retains the shape to which it has been bent.

On account of the difficulty of handling a red hot blank however and of determining with precision its exact conformity to the shape desired, especially when the expansion of the metal is considered and when the article to be produced is small, the above indicated method has proved unsatisfactory in many instances and the chief feature of this invention relates to a new method of forming articles of the above indicated description with precision and exactness. This is accomplished by bending the metallic blank while cold to the shape desired and holding it in the shape to which it has been bent while applying heat thereto to set it in said shape. Any desired holding means may be utilized for maintaining the blank as bent between the operations of bending and setting and the properly shaped blank

may be subjected subsequently to any suitable hardening process if desired.

Another feature of the invention relates to the novel method of supporting a blank as it is bent and of holding it in the proper shape, and a further feature relates to the method of supporting and holding a blank as bent, whereby the supporting and holding means are simultaneously removed as the blank is set in its new shape. This is accomplished by securing the blank as bent to a plate, block or frame of some material preferably having a comparatively low melting point, such as lead. Any preferred means may be utilized for securing the blank in position, such as stops driven into the block to which the blank is secured. The block with the blank secured in position thereto is then exposed to a temperature sufficient to set the blank, preferably by being immersed in a medium which is maintained at the necessary temperature. In case a plate or block of a metal such as lead, is utilized for the support of a bent blank, said plate with the blank in position thereof may be lowered into a bath of melted lead which quickly raises the blank to a cherry red heat, sufficient to take out any springiness or tendency to return to its former shape which may remain in the blank, while at the same time the block on which the blank was mounted is melted and the blank floats on the surface of the fluid metal from which it may be removed by any suitable method.

For the sake of illustration the method above referred to will be described in connection with the manufacture of a steel die to be used in dieing out leather, felt, paper or other sheet material, but it is to be understood that the method is by no means limited to use in connection with the manufacture of articles of the above class, being applicable also to many others, such as springs, raceways for eyeletting machines and generally wherever the blank undergoes a permanent change in form during the manufacture of the article.

In the accompanying drawing I have illustrated the manufacture by a preferred form of my new method, of a die such as above referred to, from a blank having the form of a narrow strip or ribbon of metal, and in said drawings: Figure 1 is a perspective view showing the blank bent in part to the

shape it is desired to impart thereto and held in position on its support, and Fig. 2 is a perspective view of the completed die.

Referring to said drawings, 2 represents the block or support preferably of some material having a comparatively low melting point, such as lead. The blank from which the article is to be made is indicated at 4 and as shown has the form of a narrow strip or ribbon of metal though its form would depend upon the form of the article to be made therefrom. As a general rule the cross-section of the blank should be substantially the same as that of the completed article. The blank is bent to the shape desired either manually or by other power and during the bending operation it is secured in position on the support 2 and held against any tendency to return to its former shape by suitable means such as retaining pins 6 which are firmly held in the material of said support and engage the sides of said blank to prevent it from springing back to its former shape. These pins will preferably be driven into the metal of the block on either side of the blank as it is bent and their position and number will of course vary with the nature and amount of the curvature imparted to the blank at any portion thereof. Preferably the bending of the blank is accompanied at each stage by positioning the appropriate retaining pins to hold the part already bent against yielding or springing in either direction.

At 8 there is indicated a mark or scratch on the surface of support 2 which indicates the shape to which the blank is to be bent and serves as a guide to show when the blank has been bent to exactly the shape desired. After the bending of the blank has been completed, and while it is held in said shape by its retaining means, it is raised to a temperature at which it loses all springiness or tendency to return to the shape it had at first, preferably by being immersed in a medium of the desired temperature such as melted lead. A bath of this composition is especially appropriate in case a lead block or plate is utilized as a support for the blank. In this case the support with the blank in position thereon is turned so that the blank is located at the under side thereof and then lowered into the bath. The block of lead being above the blank causes said blank to be entirely immersed in the melted lead of the bath, where it is quickly raised to a temperature sufficient to remove all springiness or tendency to return to its original shape. At the same time, the metal of the block is melted and joins the melted metal of the bath, and the blank is freed from its holding means and floats on the surface of the bath from which it is removed by any convenient method.

To complete the die it is necessary to braze

its ends together, and to temper it, but as these are both well known processes and, in their specific form constitute no part of the present invention, they need not be specifically described herein.

The term "setting" used in the present specification with reference to the blank should be construed to cover the operation of removing from the blank the internal stresses incident to the cold bending thereof, which stresses, if not removed, would have a constant tendency to distort the finished article.

Having fully described my invention, what I claim as new and desire to secure by Letters Patent is:

1. The method of forming cutting dies from strip steel which consists in marking on a metallic plate the outline required in the die, bending a strip of steel step by step, while cold, to said outline and applying heat to the blank so formed for setting it in such shape.

2. The method of forming cutting dies from strip steel which consists in marking upon a fusible plate the outline required in the die, securing a strip of steel, while cold, to said plate in conformity with said outline and applying heat to the blank so formed and to said plate for setting the blank and melting the plate.

3. The method of forming articles of metal which consists in bending a blank to the desired shape during the bending operation, applying means for maintaining the blank accurately in such shape, and setting the blank so that it will of itself retain its shape.

4. The method of forming articles of metal which consists in bending a blank to the desired shape during the bending operation, applying means for maintaining the blank accurately in such shape, and applying heat for setting the blank so that it will of itself retain its shape.

5. The method of forming articles of metal which consists in bending a blank to the desired shape during the bending operation, applying means for maintaining the blank accurately in such shape, and applying heat for setting the blank so that it will of itself retain its shape, and removing the blank retaining means.

6. The method of forming articles of metal which consists in bending a blank to the shape desired, supporting the blank as bent on a block of material having a comparatively low melting point by successively inserting fasteners during the bending operation and applying heat to the blank and its support to set the blank and to melt the block on which said blank is supported.

7. The method of making dies which consists in bending cold a strip of steel into the required outline, during the bending op-

eration securing the strip progressively to a lead block, inverting the block and the attached blank, and finally immersing them with the block on top in a lead bath to set the blank and release it from the block.

5. 8. The method of forming articles of metal which consists in bending a blank step-by-step to the shape desired, securing the blank to a block of material having a 10 comparatively low melting point by fasteners applied at each successive step of the bending operation, and immersing the blank and its support in a medium of sufficient temperature to set the blank in the shape 15 desired and remove its support.

9. 9. The method of forming articles of metal which consists in bending a blank to the shape desired, mounting the blank as bent on a block of material having a comparatively low melting point, and immersing the blank and its support in a bath of the same composition as the block on which the bent blank is mounted to set the blank 20 and to melt its support.

10. The method of forming articles of metal which consists in bending cold to the required outline a strip of steel, securing the strip in its bent form by a succession of fastening devices set in position during the bending operation and applying heat to the 25 blank so formed for setting it in shape.

11. The method of forming articles of metal which consists in bending cold to the required outline a strip of steel and during the bending operation securing said strip 30 with its edge against a metallic plate by fastening devices acting on the flat surfaces of said strip, applying heat to the blank 35 formed by the bent strip for setting the blank in shape and removing said fastening 40 devices.

In testimony whereof I have signed my name to this specification in the presence of two subscribing witnesses.

DANIEL N. PRIME.

Witnesses:

HERBERT W. KENWAY,
ARTHUR L. RUSSELL.

It is hereby certified that in Letters Patent No. 1,114,384, granted October 20, 1914, upon the application of Daniel N. Prime, of Lynn, Massachusetts, for an improvement in "Methods of Making Articles of Metal," errors appear in the printed specification requiring correction as follows: Page 2, lines 99, 106, and 113, after the word "shape" insert a comma; same page, lines 100, 107, and 114, strike out the comma; and that the said Letters Patent should be read with these corrections therein that the same may conform to the record of the case in the Patent Office.

Signed and sealed this 16th day of February, A. D., 1915.

[SEAL.]

J. T. NEWTON,

Acting Commissioner of Patents.
